UNITED STATES PATENT OFFICE.

WALTHER NERNST, OF GÖTTINGEN, GERMANY, ASSIGNOR TO GEORGE WESTINGHOUSE, OF PITTSBURG, PENNSYLVANIA.

ELECTRICAL GLOW-LIGHT.

SPECIFICATION forming part of Letters Patent No. 623,811, dated April 25, 1899.

Application filed October 2, 1897. Serial No. 653,849. (No model.)

To all whom it may concern:

Be it known that I, WALTHER NERNST, a subject of the German Emperor, and a resident of Göttingen, Germany, have invented 5 certain new and useful Improvements in Electrical Glow-Lights, of which the following is a specification.

My invention while it relates generally to the class of electric-lighting apparatus in 10 which conducting materials are heated to incandescence by the passage of electric currents differs therefrom in many important respects.

The incandescent electric lamps which have 15 heretofore been used commercially comprise an attenuated filament of carbon inclosed in a chamber from which the air has been exhausted. Numerous attempts have been made to produce a filament for an incandescent lamp which could be used in the open air, but thus far without any practical success. It has been found necessary to inclose 20 all these materials in chambers freed from oxygen; otherwise they are rapidly consumed.

They, moreover, have the capacity of emitting 25 in the form of light only a small portion of the electrical energy consumed in maintaining them in an incandescent condition. I have found that certain of the dry 30 conductors of the second class or dry electrolytes—that is to say, materials which when in a conducting condition conduct current by electrolytic action—will when heated to an incandescence under suitable conditions become 35 sufficiently conducting under moderate electrical pressures to permit the passage of sufficient electric current to maintain them in such heated conducting state and that the light given off thereby may be much greater 40 per unit of electrical energy than is secured from electric conductors of the first class.

It is, for example, possible to bring such substances as lime, magnesia, zirconia, and other of the rare earths, which are examples of dry 45 electrolytes, to a conducting condition by the application of external heat—such, for instance, as may be obtained from an alcohol-lamp or a gas-flame—and if traversed by an electric current while in such heated condition 50 they will be brought to an intense white heat and maintained in that condition by the pas-

sage of the current. They, moreover, have the capacity of withstanding these very high temperatures even while exposed to the open air, so that exhausted receptacles or those filled 55 with poorly-conducting gases are not necessary, although permissible, with my invention. I have, for example, by external means heated in the open air a small hollow cylinder of burnt magnesia of seven millimeters 60 length and 1.5 millimeters thickness to a conducting temperature and with a current of less than one-third of an ampere at one hundred and eighteen volts pressure obtained a light much greater than that of the present 65 commercial sixteen-candle-power incandescent lamp.

My new form of lamp is capable of being operated by either alternating or continuous currents; but the former have for some purposes 70 been found more desirable, as usually the lamp will endure longer under the influence of an alternating than of a continuous current.

Inasmuch as the materials referred to are 75 essentially insulators at ordinary temperatures, it is necessary that they be brought to a comparatively high temperature before they will begin to act as conductors; but when they are brought to a conducting condition 80 and current is permitted to traverse them their temperature and incandescence is still further increased and their resistance lowered. The external heat may be withdrawn when the light-giving body has itself become 85 sufficiently conducting to convey the current; but in some cases it may be desirable to continue the external heat also.

In the German patent of Jablochhoff, No. 1,630, there is suggested the possibility of 90 heating a kaolin strip or plate placed between two conductors by means of the electric spark of an induction-coil, the suggestion being that thereby one part or line of the kaolin plate or strip will thus become a conductor of very 95 high resistance; but this method is not capable of commercial use and differs from my method and the lamp embodying the same in the fact, among others, that kaolin is easily melted and that my illuminant is primarily 100 brought to a conducting temperature throughout and not along merely a line or portion

thereof, and my form of lamp permits the use of currents of much lower pressure. It has also been proposed (United States Patent No. 322,033) to heat a small section of the length 5 of a strip of refractory material by contact with the tip of a carbon pencil heated by the passage of an electric current and as the pencil dissipates establish a current through it and the heated section of the refractory strip; 10 but this form of construction differs from mine, among other things, in being much more complicated and uncertain in its results and in being dependent upon the shifting of a movable contact between the heating-body 15 and the illuminant, which involves an irregular and imperfect contact and undue resistance and diminishes the economy and durability of the lamp, and, moreover, the contact of the heated carbon with the heated strip 20 will quickly reduce and disintegrate the latter.

The accompanying drawing illustrates one method of employing my invention.

In the drawing, A represents a base carrying two binding-posts B' B². The binding- 25 posts are respectively designed to be connected with the conductors of a suitable electric circuit supplied with the desired pressure—say one hundred or two hundred volts. Greater or less electrical pressures may, how- 30 ever, be employed. Conductors S' and S² are connected with the respective binding-posts B' and B². Between the conductors S' S² there is mounted the light-giving body C, 35 which is here shown as consisting of a small bar, rod, or cylinder and is composed of such dry electrolyte or rare earth as hereinbefore described. The conductors S' and S² may be elastic, if desired, so as not to subject the body C to undue strains. 40 For the purpose of heating the light-giving body C to the proper temperature for rendering it conductive under the influence of the electrical pressure to which it is subjected the flame of a lamp C' may be used. Any other 45 suitable device may be employed for applying the initial external heat; but it should be noted that the initial heat must be imparted by

means separated from the body C, since any material placed in actual contact with the dry electrolyte C will either itself be decomposed 50 or driven off by the intense heat developed when that body is traversed by an electric current or result in a reduction or disintegration of the electrolyte composing the light-giving body.

55

I claim as my invention—

1. An improved electrical incandescent lamp, consisting of a strip of material which is an insulator at ordinary temperatures and becomes a good conductor and luminant at 60 high temperatures, combined at its extremities with fixed terminals for conducting current through the same, and with a heat-producing structure separate from the luminant and operating to raise all parts of the strip between 65 the fixed terminals to a conducting temperature prior to the passage of the illuminating-current substantially as described.

2. The method of producing light by the passage of an electric current through a strip 70 of material which is a non-conductor at ordinary temperatures, but becomes a good conductor and luminant at high temperatures which consists in heating the same throughout, by a source of heat separated from the 75 luminant, until it becomes a good conductor, and then maintaining its conductivity and luminosity by the passage of an electric current, substantially as described.

3. An electric lamp consisting of a current- 80 carrying strip of material which is an insulator at ordinary temperatures and a relatively good conductor at an incandescence temperature and heating apparatus separated therefrom and arranged to heat the strip to a conducting temperature throughout its entire section.

Signed at Berlin this 18th day of September, 1897.

WALTHER NERNST.
